UNITED STATES PATENT OFFICE.

HARRY H. PODJUS, OF CHICAGO, ILLINOIS.

CLOTHESLINE GRIP.

Application filed July 15, 1922. Serial No. 575,227.

To all whom it may concern:

Be it known that I, HARRY H. PODJUS, a citizen of the United States, and a resident of the city of Chicago, in the county of Cook and State of Illinois, have invented certain new and useful Improvements in a Clothesline Grip; and I do hereby declare that the following is a full, clear, and exact description of the same, reference being had 10 to the accompanying drawings, and to the numerals of reference marked thereon, which form a part of this specification.

This invention relates to a fastening device for holding a clothes line such as are 15 secured to the sides of buildings or the tops or sides of posts or fences to support the line for the usual purpose.

It is an object of this invention to provide a fastening of the kind described in which 20 the line can be quickly and easily put into place.

It is a further object of this invention to devise a fastening of the sort described in which the clothes line may be readily put 25 into place even though the fastening is above the ordinary reach of the operator.

It is a further object of this invention to provide a fastening for a clothes line with a guiding surface by which the line 30 shall be led downward into the proper position for fastening.

It is a further object of this invention to devise a fastening in which the line shall be held by the pinching action of a cam 35 and in which the line will be guided to its position between the pinching parts by suitable surfaces.

It is a further object of this invention to provide a fastening of the sort described 40 in which the floor of the passage through which the clothes line goes shall be oblique for ready drainage.

Other and further important objects of 45 this invention will be apparent from the disclosures in the drawings and specification.

The invention (in a preferred form) is illustrated in the drawings and hereinafter more fully described.

On the drawings:

Figure 1 is a front view of one form of the invention.

Figure 2 is a side view of the same.

Figure 3 is a top plan view.

Figure 4 is a section upon the line 4—4 55 of Figure 1.

Figure 5 is a front view, and Figure 6 an edge view of a modified form.

As shown on the drawings:

The grip has a base plate 10 provided 60 with holes 11 for the reception of screws to attach the base plate to a post, to the side of a building or fence, or to any other suitable support. In the form illustrated in Figures 1 to 4, midway of the base plate 65 is a shelf 12 preferably integral with the base plate. For the further support of the shelf a web 13 is provided which is also integral with the base plate.

Integral with the upper portion of the 70 base plate 10 are a pair of side members 15 which project forwardly to form a semi-circular wall around the back of the shelf 12, as may best be seen in Figure 4. The right hand portion of this semi-circular 75 wall is toothed, as shown at 16 in Figure 4, and the left hand portion is somewhat enlarged so that the wall does not present a true semi-circle. The flaring character of the left hand portion is illustrated at 17 80 in Figure 4. At the very edges of the side members 15, they are turned more sharply outward, as shown at 18.

The shelf 12 is provided with a pivot 19 which may be secured in place by a cotter 85 pin 20 or in any other desired way. Integral with the upper part of the pivot 19, or secured thereto in any desired manner, is a rotating member 21. The lower portion of this member is of a general semi-circular cross section, as is best seen in Figure 4. The curved face of the lower portion of this member is provided with teeth 22 which are seated in a groove 23 which is shown in Figures 1 and 2. The 90 teeth 16 are also formed in a curved way to constitute a co-operating wall so that between the teeth 22 and 16 there is a passage of approximately circular cross section for the clothes line. The pivot 19 is 100 eccentric to the semi-circle of the rotatable part 21, so that when it rotates one end or the other of the circular passage for the rope will be constricted.

The upper portion of the rotatable member 21 is brought to a blunt point, as shown 105

at 25, and the portion between the point 25 and the groove 23 is rounded to form a guiding surface leading from the point 25 to the groove 23. A lug 26 projects downward 5 from one point in the bottom of the member 21, and a notch 27 is formed in the shelf 12 to receive this lug.

In the form shown in Figures 5 and 6, the shelf 32, instead of being horizontal as is 10 the shelf 12, is placed obliquely. Its ends are united with the base plate 10 by means of oblique webs 33. A pivot 39 has a cotter pin 40, by means of which a rotatable member 41 is mounted upon the shelf 32. A 15 flange 45 projecting partly from the base 10 and partly from the shelf 32 co-operates with the part of the rotatable member nearest the shelf 32 to form a passage for the clothes line. This flange is provided with 20 teeth 46 along one wall of the passage for the rope. The shelf 32 forms an adjacent wall for this passage, and the rotating member 41 has a groove 53 which forms the wall of the passage opposite the teeth 46. The 25 groove 53 may or not be supplied with teeth corresponding to the teeth 22, as is desired.

The rotating member 41 has a horn 55 extending from the top of the rotating member. The tip of this horn is not a sharp 30 point but is bluntly rounded. The surfaces approaching the tip are gradually curved so as to lead the rope to the groove 53. A stop 56 integral with the rotating member 41, and co-operating with a notch 57 in the 35 shelf 32 is provided to limit the motion of the rotating member 41.

In the operation of the device, the base plate 10 is screwed to the support. Preferably it is located as high as can be conveniently reached or a little higher. The operator makes a loop or a bight in the clothes line and places or throws the bight over the top 25 of the rotating member 21 or the top 55 of the rotating member 41. The free 45 end 60 of the clothes line is then pulled. The other portion 61 of the clothes line has been previously secured in any desired manner to any suitable fastening. A pull upon the end 60 with the portion 61 of the clothes line made fast results in a tension which causes the clothes line to slip downward over the curved surface of the member 21 or 41 and so arrive in the groove 23 or 53. A further pull upon the free end 60 of the 50 clothes line causes the rotatable member to rotate about the pivot in a clockwise direction, as seen in Figure 4. The stop 26 arriving in the notch 27 or the stop 56 arriving in the notch 57 causes the rotating member 60 to come to rest in a position in which the 55 passage for the clothes line is of ample width throughout. The pull upon the free end 60 of the clothes line is continued until the portion 61 has the desired degree of tension. 60 The end 60 is then slackened and the ten-

sion in the portion 61 causes the clothes line to travel clockwise, as seen in Figure 4, a very small distance. This travel rotates the member 21 about the pivot 19 and causes the right hand portion of this member, as seen 70 in Figure 4, to pinch the clothes line between said member and the side member 15, with the result that the clothes line is held firmly in place by the pinching action and the effect of the teeth 16 and 22.

The enlargement of the passage for the clothes line, as shown at 17, and the flaring character of the end portions 18 give play 80 in the untoothed portions of the passage for the clothes line so that the direction of the end 60 or of the portion 61 need not be as illustrated in Figures 3 and 4, but may vary even as much as 90 degrees to the right or left of this position. The fact that the roomier part of the passage is away from the free end of the rope also assists in leading the rope into the passage as tension is applied to the end 60.

When it is desired to release the clothes line, the end 60 is pulled until the member 21 has rotated to the position where the passage is of ample width throughout. By grasping the portion 61 and pulling towards the grip the end 60 may be slackened without causing the member 21 to rotate back to the fastening position. When this is done, the member 60 may be caused to snap upward out of the groove 23 by giving it a slight twitch and be brought over the top 25 of the member 21. If the operator is quick, he may slacken the end 60 and give it a twitch in the way just described without the necessity of grasping the portion 61 and pulling toward the fastener in order to release the clothes line. Also if the grip is 105 located low enough for the operator to do so he may exert an upward pull on the end 60 which will rotate the member 21 to releasing position and then will cause the rope to slip up and out.

In the form shown in Figures 5 and 6, the same method of operation applies except that the pull upon the end 60 is directed obliquely downward and slightly toward the right. In releasing the rope from this form of grip the method by slackening and twitching already described may be used or the end 60 may be pulled farther to the right which will result in the rope slipping out. In this form, if the fastener becomes wet from the rain or becomes covered with snow, the rain water or the melting snow will quickly drain out of the passage for the clothes line, so that this passage is not likely to become rusty and so to mark the clothes line.

I am aware that numerous variations in details may be made and that the variations may be carried through a wide degree without departing from the spirit of this invention.

I claim as my invention:

1. In a clothes line gripping device, a rotatably mounted gripping member having a height more than twice the diameter of the clothes line the upper portion of said member terminating in a bluntly rounded point and forming a guide for the line to gripping position.
2. In a clothes line gripping device, a rotatably mounted gripping member, having a height more than twice the diameter of the clothes line, the upper portion of said member terminating in a bluntly rounded point, and gently curved guiding surfaces extending from said point downward to gripping position.
3. In a clothes line gripping device, a rotatable gripping member having a groove for the passage of the clothes line, the height of said member being more than twice the width of said groove, a bluntly rounded point at the upper end of said member, and gently curved guiding surfaces extending from said point to the upper edge of said groove.
4. In a clothes line gripping device, a rotatable member having a groove for the passage of the clothes line, the height of said member being more than twice the width of said groove, a bluntly rounded point at the upper end of said member, gently curved guiding surfaces extending from said point to the upper edge of said groove, a base plate, a grooved surface and a shelf integral with said base plate, said grooved surface co-operating with the groove in said rotatable member to afford a passage for the clothes line, and said rotatable member having an eccentric pivot passing through said shelf, and ratchet formed teeth upon the opposing walls of said passage to prevent backward motion of the clothes line.
5. In a clothes line gripping device, a rotatable member having a groove for the passage of the clothes line, the height of said member being more than twice the width of said groove, a bluntly rounded point at the upper end of said member, gently curved guiding surfaces extending from said point to the upper edge of said groove, a base plate, a grooved surface and a shelf integral with said base plate, said grooved surface co-operating with the groove in said rotatable member to afford a passage for the clothes line, said rotatable member having an eccentric pivot passing through said shelf, and ratchet formed teeth upon the opposing walls of said passage to prevent backward motion of the clothes line.
6. In a clothes line gripping device, a base plate, a shelf integral with said base plate and extending at an oblique angle to the vertical dimension of said plate, and a rotatably mounted gripping member pivoted on said shelf, said member and said base plate being provided with co-operating surfaces to form a passage for the clothes line, the wall of said passage between said co-operating surfaces being formed by a portion of said shelf.

In testimony whereof I have hereunto subscribed my name in the presence of two subscribing witnesses.

HARRY H. PODJUS.
